Primary Examiner — T Chase Nelson*Assistant Examiner* — Sydney Margaret Parsley(74) *Attorney, Agent, or Firm* — Dorsey & Whitney LLP(57) **CLAIM**

The ornamental design for an accessory for a ladder as shown and described.

DESCRIPTION

FIG. 1 is a front perspective view of an accessory for a ladder;

FIG. 2 is a rear perspective view thereof;

FIG. 3 is an enlarged, front view thereof;

FIG. 4 is an enlarged, rear view thereof;

FIG. 5 is an enlarged, right side view thereof;

FIG. 6 is an enlarged, left side view thereof;

FIG. 7 is an enlarged, top view thereof; and,

FIG. 8 is an enlarged, bottom view thereof.

The broken lines in the figure views show portions of the accessory for a ladder that form no part of the claimed design.

1 Claim, 8 Drawing Sheets(56)
